UNITED STATES PATENT OFFICE.

JAMES L. BALDWIN, OF CHICAGO, ILLINOIS.

CASH CARRIER.

Application filed January 9, 1922. Serial No. 527,964.

To all whom it may concern:

Be it known that I, JAMES L. BALDWIN, a citizen of the United States, residing at Chicago, in the county of Cook and State of Illinois, have invented new and useful Improvements in Cash Carriers, of which the following is a specification.

This invention relates to apparatus employed in stores and other mercantile establishments for the transportation of money or parcels, the same consisting of an elevated track upon which carriers travel from various sending terminals or stations to a receiving station, such as the cashier's department, the bundle wrapping department, etc.

The invention relates more particularly to a carrier system in which the propulsion of the carrier is effected by some interposed mechanism which is manually operable, and the invention has been illustrated in connection with a cash carrier.

It is the object of the invention to provide a novel and improved mechanism for moving the carrier in a vertical direction from one floor to another above where the cashier's department or other terminal or receiving station may be located, or to allow it to continue its way along another horizontal track on such upper floor.

The elevating means are power operated, and consist in a combination and arrangement of parts to be hereinafter described and claimed.

In order that the invention may be better understood, reference is had to the accompanying drawings forming a part of this specification, and in said drawings,

Figure 1 is an elevation of the apparatus; Fig. 2 is an enlarged front elevation of a carrier-elevating means;

Fig. 3 is a side elevation thereof;

Fig. 4 is a view similar to Fig. 3 showing the carrier supported by the elevating means;

Fig. 5 is an inverted plan view of a power-controlling mechanism;

Fig. 6 is a front elevation of said mechanism;

Fig. 7 is a side elevation thereof, and Fig. 8 is an enlarged side elevation of a detail as viewed from the line 8-8 in Fig. 7.

Referring specifically to the drawing, 10 denotes the mechanism at the sending station of the apparatus, and as no claim is made for such mechanism it need not be de-

scribed in detail. An ordinary cash carrier is shown at 11 and it is adapted to be sent along the overhead track 12 by an impulse imparted to it by the mechanism at the sending station. At 13 is shown the floor of a room or loft which is located above the room in which the mechanism 10 and the track 12 are located, and hence to get the carrier to such upper floor, an elevating means has 65 been provided, this being necessary owing to the fact that the propulsive effect of the mechanism 10 is not sufficient to send the carrier 11 upwardly the required distance. A suitable distance above the floor is positioned a base board 14 which supports an electric motor 15 and other parts to be presently described. The site of these parts may be considered the location of the receiving or cashier's station, so that when the carrier 75 11 reaches the same it may be removed and sent back to the sending station at 10. The base board 14 is supported by a standard 16 rising from the floor 13 a suitable distance to locate the base board at the desired 80 height.

As shown at 12^a in Fig. 1, the track 12 has an upward curve where it approaches the site of the receiving station, and here the floor 13 has depending hangers 17 and 18 forming supports for the track. The curved portion of the track extends to the floor and passes through a hole therein, and alongside said portion of the track and parallel thereto is another track 19 on which the elevator 90 to be presently described is mounted for travel. The track sections pass through the floor, and beneath the same they are held in laterally spaced relation by arches 20 and 21, the former being carried by the hangers 17, 95 and between the arches the track sections are connected to flat plates shown at 22 and 22^a. The track section 19 above the floor 13 is fitted with a plate 23 which is carried by a depending hanger 23^a. The track section 100 12^a terminates at the bottom of the base board 14, and to the bottom of the latter is secured a downwardly arched supporting member 24 to which the hanger 23^a is secured.

The support 24 carries a depending rod 25 on which is mounted a support 26 for a latch hook 27 the same being pivoted, as shown at 27^a and provided with a releasing lever 28. The support 26 has a bottom extension 29 110 provided with a side lug 29^a which is apertured to let the track 12^a through, and the

latter also passes through the support. A spring 30 holds the latch hook 27 pressed against the lug 29^a. The forward end of the carrier 11 has a keeper aperture 11^a for the latch hook 27, and the latter is so located that it snaps into the keeper aperture when the carrier reaches the same, it being understood that the latch hook is positioned in the path of the forward end of the carrier 10 so as to intercept the same. The latch hook is at the limit of the upward travel of the carrier, and to release the latter for descent it is necessary only to swing the lever 28 manually, which disengages the latch hook 15 and frees the carrier so that it may descend by gravity down the track section 12^a. With the support 26 is associated a rubber block 31 to receive the impact of the carrier, the forward end of the latter striking the 20 block as it is caught by the latch hook 27. The impact or blow of the carrier is also cushioned by making the rod 25 slideable and placing a coiled spring 32 around the same to resist its upward movement.

25 In order to move the carrier 11 up the ascending portion 12^a of the track to the latch hook 27, which latter is its final destination, a power-driven elevator is provided, the same being mounted to travel on the 30 track 19. This elevator is normally positioned where the track section 12^a starts to ascend, and when the carrier reaches the same it is caught by the elevator and transported to its final destination.

35 The elevator comprises a base 33 having wheels 34 which engage the track 19 on opposite sides, and on one side of the base is a pivoted holder 35 for the carrier 11, whereas the opposite side has two longitudinally 40 spaced guard arms 35^a which serve as seats for the wheeled side of the carrier.

45 The holder 35 is yoke-shaped and it is pivoted to the base 33 as shown at 33^a to swing transversely of the direction of travel of the carrier 11, the latter having the usual side receptacle 11^b in which the cash receptacle is placed. The holder is so located that its two branches or arms 35^a may straddle the part 11^b as shown in Fig. 4.

50 Fig. 3 shows the elevator in carrier-receiving position. It will be noted that the holder has been swung so that the free ends of its arms 35^b face in the direction the carrier 11 is approaching, and when the latter 55 reaches the holder, the part 11^b enters between the arms. The impetus of the carrier causes the holder to swing so that the arms 35^b assume the position shown in Fig. 4, they now being in front of and to the rear of the 60 part 11^b, whereby the carrier is coupled to the elevator so that it will be carried along with the elevator when the latter starts to go up. The holder 35 is locked in the last described position by a latch 36 pivoted to the 65 base 33 as shown at 37, and engaged by a

spring 38 which tends to swing it to locking position. The back of the holder has a shoulder 39 engageable by the latch, and the holder has a second shoulder 39^a which is engageable by the latch when the holder is in open or carrier-receiving position as shown in Fig. 3, to limit its swing in this direction. On the track plate 22^a is an abutment 40 for controlling the operation of the latch 36 as will be presently described. 70 75

The elevator receives motion from a cable, belt or similar propulsion element 41, the same being connected to the front and the rear of the elevator, as shown in Fig. 1. It will therefore be evident that when the cable 80 is in motion the elevator is carried along with it. The cable is driven by the motor 15, it being trained over a pulley 42 on the motor shaft. The cable 41 passes over a bottom pulley 43 supported by the arch 20, 85 and the arch 21 carries a pair of pulleys 44 for holding the two runs of the cable spaced. The arch 20 also carries a spring bumper rod 45 which is struck by the elevator at the limit of its downward travel to carrier-receiving position, and at the end of its upward travel the elevator strikes a similar bumper 46 carried by the support 24. 90

95 In operation, assuming the elevator to be down in receiving position as shown in Fig. 3, when the carrier 11 reaches the elevator, the part 11^b enters between the arms 35^b of the holder and the latter by the impact of the carrier then swings to the position shown in Fig. 4, in which position it is locked by the latch 36. The elevator now ascends, the cable 41 having been put in motion by means 100 to be described hereinafter, and carries the carrier along with it. When the elevator reaches the limit of its upward travel it strikes bumper 46 and the carrier is caught and held by the latch hook 27, it being understood, of course, that the cable 41 is stopped at the same time by means later described. When the cashier or other operator desires to return the carrier, the hook 27 is disengaged, whereupon the carrier and the elevator to which it is still coupled by the holder arms 35^b descend by 105 gravity, and the elevator now goes back to receiving position. When the elevator reaches the limit of its downward travel it strikes the bumper 45. The latch 36 is now also automatically operated to unlock the holder or coupling member 35 110 and thus free the carrier 11 so that it may continue its travel to the sending station, free of the elevator. This operation of the latch is effected by a rearwardly projecting finger 36^a thereon striking the abutment 115 40. When this action takes place, the latch 120 swings to clear the shoulder 39 which leaves the holder 35 free, and the inertia of the carrier causes its part 11^b to swing the holder to clear the same, the holder now 125 130

again assuming the position shown in Fig. 3, in which position it is held by the detent as it snaps on the shoulder 39^a. The holder is now ready to receive the carrier on its next trip. The latch has a second rearwardly projecting finger 36^b which comes beneath the abutment 40 when the latch swings to allow the holder 35 to release the carrier as shown in Fig. 3, and thereby prevents a rebound of the elevator as it strikes the bumper 45. The elevator therefore remains down, and the holder remains open and ready to receive the carrier on its return trip. The latch finger 36^b comes beneath the abutment 40 after the elevator strikes the bumper 45 and before the bumper spring can expand to cause a rebound of the elevator. It will therefore be evident that the elevator is given an initial upward impulse when it is freed by the finger clearing the abutment 40, this action taking place when the carrier again reaches the elevator and its part 11^b swings the holder arms 35^b from the receiving position shown in Fig. 3 to the coupling position shown in Fig. 4.

The initial upward movement of the elevator just described is utilized to actuate a mechanism which controls the power source by which the elevator propelling cable 41 is driven. This mechanism comprises the following parts:

The circuit of the motor 15 which drives the propelling cable 41 of the elevator is controlled by a switch having the usual "On" and "Off" buttons 47 and 48 which are so connected that when one button is pushed in the other button moves outwardly, and vice-versa. This switch is so mounted and supported on the base board 14 that the buttons are beneath the same and facing downwardly. The motor 15 is positioned on top of the base board 14 and, the latter has holes 49 and 50 through which the two runs of the cable 41 pass to the motor pulley 42.

On the under side of the base board 14 is mounted a depending bracket member 51 having two vertically spaced and laterally extending arms 51^a and 51^b. The side from which these arms extend is concave and in vertical alignment with the hole 49 to serve as a slideway for an abutment 52 carried by that portion of the cable 41 which runs upward in said hole, said abutment having an upward taper as clearly shown in Figures 6 and 7.

To the arm 51^b is pivoted, as shown at 53, an upwardly extending member 54 having its upper end forked and carrying a roller 54^a which is opposite the concave side of the member 51, with the abutment 52 seating between these parts.

At 55 is shown an actuator for the switch button 47, the same being a finger extending laterally from a member 56 pivoted at

56^a to the arm 51^a and depending from the latter alongside the member 54 but spaced therefrom. Between member 54 and member 56 is interposed a coiled spring 57 anchored to said parts in any suitable manner. The member 54 therefore serves as a swinging abutment for one end of the spring 57.

The member 56 carries a latch lever 58, the same being pivoted to the lower end thereof, as shown at 58^a, and between the tail of said lever and a side lug 56^b on member 56 is interposed a spring 58^b tending to swing the lever in one direction.

The latch lever 58 has a laterally extending arm 59 provided with a slot 59^a having a side notch 59^b at one end into which extends a side pin 60 on the arm 51^b. The extremity of the latch lever carries a pivoted dog 61 which is normally held in an advanced position by a spring 62 so as to locate its extremity beneath the abutment 52 as shown in Fig. 6. The outward swing of the dog is limited by a shoulder 61^a at its pivoted end.

Fig. 6 shows the position of the parts 90 when the motor circuit is open, the "On" switch button 47 being in inactive position. The abutment 52 is between the roller 54^a and the concave side of bracket member 51 which latter forms a stationary abutment 95 opposite the pivoted abutment 54. The lever 56 has been swung in the direction of the abutment 54 to compress spring 57, and lever 55 is locked in this position by the notch 59^b of latch 58 engaging the pin 60. 100 When the hereinbefore described initial impulse or upward movement of the elevator occurs, that portion of the cable 41 to which abutment 52 is secured goes down a corresponding distance, with the result that 105 the bottom of the abutment strikes the dog 61 and trips the latch 58 to release lever 56 which latter is then swung by spring 57 to press the finger 55 upwardly and thereby push in the "On" switch button. The motor circuit being now closed, the cable 41 is operated to carry the elevator and its load upwardly to its destination, and when reaching the latter, the motor circuit is automatically broken by a mechanism which 115 will now be described.

On the cable 41 is a second abutment 63 similar to abutment 52 but made up of a coiled spring which is closely wound. The abutment 63 is interposed in that portion 120 of the cable 41 which travels upwardly when the elevator is going up, and it is close to the elevator and in advance thereof so as to function at the time the elevator reaches its destination.

On the under side of the base board 14 is mounted an actuator mechanism for the "Off" switch button 48, said mechanism being controlled by the abutment 63. This mechanism comprises a base 64 having a 130

pair of depending branches 65 which are connected at their extremities to form a jaw 66, opposite which latter is a roller 67 carried by a pivoted fork 68 having its rear end formed with a finger 69 positioned to press on the button 48.

When the elevator reaches its destination on its upward travel, the abutment 63 is forced between the jaw 66 and roller 67, 10 with the result that the finger 69 swings to press the button 48 in, thereby opening the motor circuit. As the button 48 is pressed in, the button 47 is of course, advanced, and this movement of button 47 swings 15 lever 56 over toward abutment 54 and places latch 58 in locking position. The "On" button 47 control mechanism is in this way restored to the normal position shown in Fig. 6, ready for the next operation. As 20 the elevator is allowed to go down back to receiving position, that portion of the cable 41 which carries abutment 52 goes up and restores the latter to the position shown in Fig. 6 between the stationary abutment 51 25 and roller 54^a, the abutment 52, as it engages roller 54^a, swinging abutment 54 back to place spring 57 under tension. As the dog 61 is pivoted, it slips to allow the abutment 52 to pass upwardly.

30 I claim:

1. In an apparatus of the kind stated a carrier elevator, an endless propulsion member to which the elevator is connected, an electric motor for driving the propulsion member in a direction to carry the elevator to its destination, a switch controlling the circuit of the motor, a switch actuator for opening the motor circuit, and means for 35 automatically effecting the operation of said actuators in succession.

2. In an apparatus of the kind stated a carrier elevator, an endless propulsion member to which the elevator is connected, an 40 electric motor for driving the propulsion member in a direction to carry the elevator to its destination, a switch controlling the circuit of the motor, a switch actuator for closing the motor circuit, a switch actuator 45 for opening the motor circuit, and means on the propulsion member for automatically effecting the operation of said actuators in succession.

3. In an apparatus of the kind stated a 50 carrier elevator, an endless propulsion member to which the elevator is connected, an electric motor for driving the propulsion member in a direction to carry the elevator to its destination, a switch controlling the 55 circuit of the motor, a switch actuator for closing the motor circuit, a switch actuator for opening the motor circuit, and means on opposite runs of the propulsion member for effecting the operation of the switch actuators in succession.

4. In an apparatus of the kind stated a carrier elevator, an endless propulsion member to which the elevator is connected, an electric motor for driving the propulsion member in a direction to carry the elevator to its destination, a switch controlling the 70 circuit of the motor, a switch actuator for closing the motor circuit, a switch actuator for opening the motor circuit, means on opposite runs of the propulsion member for effecting the operation of the switch actuators in succession, said means on one run 75 controlling one actuator and the means on the other run controlling the other actuator.

5. In an apparatus of the kind stated a carrier elevator, an endless propulsion member to which the elevator is connected, an electric motor for driving the propulsion member in a direction to carry the elevator to its destination, a switch controlling the 80 circuit of the motor, a switch actuator for closing the motor circuit, a switch actuator for opening the motor circuit, means on opposite runs of the propulsion member for effecting the operation of the switch actuators in succession, said means on one run 85 controlling one actuator, the means on the other run controlling the other actuator, and means for imparting an initial impulse to the propulsion member for effecting the operation of the switch actuator which closes 90 the motor circuit.

6. In an apparatus of the kind stated, a carrier elevator, an endless propulsion member to which the elevator is connected, an 100 electric motor for driving the propulsion member in a direction to carry the elevator to its destination, a switch controlling the circuit of the motor, said switch having circuit closing and opening buttons which are 105 connected to move simultaneously in opposite directions, actuators for said buttons, and means for automatically effecting the operation of said actuators in succession.

7. In an apparatus of the kind stated, a 110 carrier elevator, a propulsion member to which the elevator is connected, an electric motor for driving the propulsion member in a direction to carry the elevator to its destination, a switch controlling the circuit of the motor, said switch having circuit closing 115 and opening buttons which are connected to move simultaneously in opposite directions, actuators for said buttons, and means on the propulsion member for automatically effecting the operation of said actuators in succession.

8. In an apparatus of the kind stated, a carrier elevator, an endless propulsion member to which the elevator is connected, an 125 electric motor for driving the propulsion member in a direction to carry the elevator to its destination, a switch controlling the circuit of the motor, said switch having circuit closing and opening buttons which are 130

connected to move simultaneously in opposite directions, actuators for said buttons, and means on opposite runs of the propulsion member for effecting the operation of the switch actuators in succession.

9. In an apparatus of the kind stated, a carrier elevator an endless propulsion member to which the elevator is connected, an electric motor for driving the propulsion member in a direction to carry the elevator to its destination, a switch controlling the circuit of the motor, said switch having circuit closing and opening buttons which are connected to move simultaneously in opposite directions, actuators for said buttons, and means on opposite runs of the propulsion member for effecting the operation of the switch actuators in succession, said means on one run controlling one actuator and the means on the other run controlling the other actuator.

10. In an apparatus of the kind stated, a carrier elevator, an endless propulsion member to which the elevator is connected, an electric motor for driving the propulsion member in a direction to carry the elevator to its destination, a switch controlling the circuit of the motor, said switch having circuit closing and opening buttons which are connected to move simultaneously in opposite directions, actuators for said buttons, means on opposite runs of the propulsion member for effecting the operation of the switch actuators in succession, said means on one run controlling one actuator and the means on the other run controlling the other actuator, and means for imparting an initial impulse to the propulsion member for effecting the operation of the switch actuator which actuates the circuit closing button of the switch.

11. In an apparatus of the kind stated, a carrier elevator, an endless propulsion member to which the elevator is connected, an electric motor for driving the propulsion member in a direction to carry the elevator to its destination, a switch controlling the circuit of the motor, said switch having circuit closing and opening buttons which are connected to move simultaneously in opposite directions, a pivoted actuator for the circuit closing button, a spring for imparting a working stroke to the actuator, a pivoted abutment between which and the actuator the spring is interposed, a latch for locking the actuator in retracted position to the abutment, a stationary abutment opposite the pivoted abutment, an abutment on the propulsion member normally positioned

between the stationary and the pivoted abutments, and into the path of which the latch extends, means for imparting an initial impulse to the propulsion member for carrying the abutment thereon in a direction to trip the latch, an actuator for the circuit opening button, and an abutment on the propulsion member for effecting the operation of the last-mentioned actuator.

12. In an apparatus of the kind stated, a carrier, an elevator for the carrier toward which the carrier travels, propulsion means for the elevator, and a holder for coupling the carrier to the elevator, said holder being positioned to intercept the carrier.

13. In an apparatus of the kind stated, a carrier, an elevator for the carrier toward which the carrier travels, propulsion means for the elevator, a holder for the carrier pivotally mounted on the elevator to swing from receiving to holding position, a latch for locking the holder in carrier-holding position, and an abutment in the path of the latch for tripping the same.

14. In an apparatus of the kind stated, a carrier, an elevator for the carrier toward which the carrier travels, propulsion means for the elevator, a holder for the carrier pivotally mounted on the elevator to swing from receiving to holding position, a latch for locking the holder in carrier-holding position, and an abutment in the path of the latch for tripping the same, said latch having means for limiting the swing of the holder to carrier-receiving position.

15. In an apparatus of the kind stated, a carrier, an elevator for the carrier toward which the carrier travels, propulsion means for the elevator, a yoke-shaped holder for the carrier pivotally mounted on the elevator to swing from receiving to holding position, a latch for locking the holder in carrier-holding position, and an abutment in the path of the latch for tripping the same, the holder having a shoulder engageable by the latch, and a second shoulder engageable by the latch for limiting the swing of the holder to carrier-receiving position.

16. In an apparatus of the kind stated, a carrier, an elevator for the carrier toward which the carrier travels, propulsion means for the elevator, and a holder for coupling the carrier to the elevator, said holder being positioned to intercept the carrier, and a catch engageable with the carrier for holding the same at the limit of the propulsion stroke of the elevator.

In testimony whereof I affix my signature.
JAMES L. BALDWIN.
